UNITED STATES PATENT OFFICE.

HAROLD G. ESSAYAN, OF BROOKLINE, MASSACHUSETTS.

DESIGN FOR AN EMBLEM, BADGE, STICKPIN, OR SIMILAR ARTICLE.

53,846.

Specification for Design.

Patented Sept. 16, 1919.

Application filed May 5, 1919. Serial No. 295,003. Term of patent 7 years.

To all whom it may concern:

Be it known that I, HAROLD G. ESSAYAN, a citizen of the United States, residing at Brookline, in the county of Norfolk and Commonwealth of Massachusetts, have invented a new, original, and ornamental Design for Emblems, Badges, Stickpins, or Similar Articles, of which the following is a specification, reference being had to the

accompanying drawing, forming part hereof, in which—

The figure is a front elevation of an emblem, badge, stickpin or similar article showing my new design.

I claim—

The ornamental design for an emblem, badge, stickpin, or similar article as shown.

HAROLD G. ESSAYAN.
